(57) **CLAIM**

The ornamental design for an electrical power converter housing, as shown and described.

DESCRIPTION

FIG. 1 is a top perspective view of an electrical power converter housing showing our new design, viewed from the front and right side;

FIG. 2 is another top perspective view thereof, viewed from the front and left side;

FIG. 3 is a bottom perspective view thereof, viewed from the front and right side;

FIG. 4 is another bottom perspective view thereof, viewed from the front and left side;

FIG. 5 is a top plan view thereof;

FIG. 6 is a bottom plan view thereof;

FIG. 7 is a front elevation thereof;

FIG. 8 is a rear elevation thereof;

FIG. 9 is a right side elevation thereof; and,

FIG. 10 is a left side elevation thereof.

In the drawings, the broken lines represent portions of the article which form no part of the claimed design.

1 Claim, 5 Drawing Sheets
